US00D690667S

(12) **United States Design Patent**
Pfeiler et al.

(10) **Patent No.:** **US D690,667 S**
(45) **Date of Patent:** **** Oct. 1, 2013**

(54) **EMERGENCY STOP BUTTON**

(75) Inventors: **Alexander Pfeiler**, Vienna (AT);
Michael Matheisl, Vosendorf (AT)

(73) Assignee: **Inventio AG**, Hergiswil NW (CH)

(**) Term: **14 Years**

(21) Appl. No.: **29/415,508**

(22) Filed: **Mar. 12, 2012**

(30) **Foreign Application Priority Data**

Dec. 14, 2011 (CH) 138492

(51) **LOC (9) Cl.** **13-03**

(52) **U.S. Cl.**

USPC **D13/174**

(58) **Field of Classification Search**

USPC D13/171, 174; D10/108; 307/139,
307/157; 315/290 R, 224, 246, 291, 294,
315/295; 200/5 A, 43.13, 43.18, 520, 530,
200/293, 296, 302.2, 314, 329, 341

See application file for complete search history.

(57) **CLAIM**

The ornamental design for an emergency stop button, as shown and described.

DESCRIPTION

FIG. 1 is an isometric view showing the front, top and one side of a first preferred embodiment of the design;

FIG. 2 is a front elevation view of a first preferred embodiment of my invention;

FIG. 3 is a rear elevation view of a first preferred embodiment of my invention;

FIG. 4 is a left-side elevation view of a first preferred embodiment of my invention;

FIG. 5 is a right-side elevation view of a first preferred embodiment of my invention;

FIG. 6 is a top elevation view of a first preferred embodiment of my invention;

FIG. 7 is a bottom elevation view of a first preferred embodiment of my invention;

FIG. 8 is an isometric view showing the front, top and one side of a first preferred embodiment of the design;

FIG. 9 is an isometric view showing the front, top and one side of a second preferred embodiment of the design;

FIG. 10 is a front elevation view of a second preferred embodiment of my invention;

FIG. 11 is a rear elevation view of a second preferred embodiment of my invention;

FIG. 12 is a left-side elevation view of a second preferred embodiment of my invention;

FIG. 13 is a right-side elevation view of a second preferred embodiment of my invention;

FIG. 14 is a top elevation view of a second preferred embodiment of my invention;

FIG. 15 is a bottom elevation view of a second preferred embodiment of my invention; and,

FIG. 16 is an isometric view showing the front, top and one side of a second preferred embodiment of the design.

The broken line showing of the environment is for illustrative purposes only and forms no part of the claimed design.
